UNITED STATES PATENT OFFICE.

BERNARD R. DUTCHER, OF NEW YORK, N. Y., ASSIGNOR TO GRAHAM-CHISHOLM COMPANY, OF NEW YORK, N. Y., A CORPORATION OF NEW YORK.

LOOSE-LEAF STAND FOR LEDGERS.

1,403,393.

Specification of Letters Patent. Patented Jan. 10, 1922.

Application filed March 19, 1920. Serial No. 364,714.

To all whom it may concern:

Be it known that I, BERNARD R. DUTCHER, a citizen of the United States, residing in New York, in the county of New York and State of New York, have invented certain new and useful Improvements in Loose-Leaf Stands for Ledgers, of which the following is a specification.

This invention relates to improvements in leaves or sheets for loose-leaf binders and to supports co-operating with the loose-leaves and with the binder for aiding in their manipulation.

My support is especially designed for use with a temporary binder or loose-leaf holder or book, and I have shown my device in use with one form of the binder; but the improvements both in the cover and the supports are capable of embodiment and are desirable for use with other forms of temporary binders and in other relations where it is desirable to facilitate the handling of loose sheets.

The main objects of this invention are:—

First, to provide an improved device which facilitates the use of temporary binders or loose sheet holders and particularly those used in accounting systems.

Second, to provide an improved device and loose-leaf which facilitates the handling or manipulation of loose record sheets and for off-setting the same from each other during such manipulation.

Third, to provide an improved device which facilitates the manipulation and handling of temporary binders and the insertion and removal of sheets therefrom.

Fourth, to provide a practical, durable, easily manufactured support of the kind mentioned above.

Other objects of the invention will appear as the description proceeds; and while herein minute details of the invention are described, the invention is not limited to these, since many and various changes may be made without departing from the scope of the invention as claimed.

In the accompanying drawing, showing by way of example, one of many possible embodiments of the invention,—

Figure 1 is a perspective view of a structure embodying the features of my invention, without a binder therein;

Fig. 2 is a plan of the same;

Fig. 3 is a side elevation;

55

Fig. 4 is a view in vertical longitudinal section on the line 4—4, of Fig. 2;

Fig. 5 is a sectional view on the line 5—5, of Fig. 2;

Fig. 6 is a perspective view of the support 60 showing the binder therein;

Fig. 7 is a side elevation of a detail; and

Fig. 8 is a face view of the loose-leaf or sheet.

My improved loose-leaf support or tray 65 is adapted for use with a loose-leaf book binder 5 (Fig. 6), comprising a pack of leaves 7 (Figs. 6 and 8) each having midway of its inner edge 8 a projecting locating tab 9, a middle perforation 10 and side 70 perforations 11, each perforation being near and equally spaced from the inner edge 8 of the leaf and equally spaced from the adjacent perforation.

Said book also comprises a pair of clamping bars 12 (Fig. 6), one on each side of said pack of leaves at said inner edges and each provided with key holes 13 at one end with locking openings registering with the middle perforation 10 and one of the 80 side perforations 11. A pair of posts 16, one of which is shown in Fig. 6, pass through said openings and the middle perforation 10 and one or the other of the side perforations 11 and are locked in said locking holes by suitable locking means comprising a squared key receiving arbor in said key holes 13. Binding or cover boards 18 are hinged to said clamping bars 12 and are adapted to cover said pack and project 90 a slight distance at the top and bottom edges of said leaves whether the leaves are off-set from each other as in the upper part of Fig. 6, or not, as in the lower part.

The tray itself comprises a pair of side 95 walls 20 (Fig. 1), a front end wall 21, and a rear end wall 22, (Fig. 4), having its upper edge 23 lower than the upper edges of the other walls. A pair of forwardly and downwardly inclined supporting strips 25 and 26 100 (Fig. 1) are secured to the inner face of said side walls and have their upper ends meeting the upper edge of said rear wall 22 and the front ends extending to near the bottom edge of the side walls 20, about a 105 fourth of the length of the side wall from the rear wall. Above the lower end portion of said strip 25 is an upper guide 27 above

and parallel to the supporting strip 25 and spaced therefrom about the thickness of the cover board 18 of the book in order to receive the cover board as in Fig. 6.

5 A hinged plate 30 (Fig. 4) is hinged to the upper edge 23 of said rear wall 22 in the plane thereof and adapted to fold over against said supporting strips 25 and 26 as in Fig. 1, and is provided with a binding 10 wire 31 (Fig. 4) beaded in the upper and side edges of the hinged plate and having at each end a guide extension 32 extending down against the outer face of the rear wall when the hinged plate is up, and extending 15 approximately in alinement with said supporting strips 25 and 26 (Fig. 1) when the hinged plate rests on the strips for aiding in supporting the cover board 18, (Fig. 6).

Obviously this hinged plate may be omitted 20 and the strips 25 and 26 extended to or near the upper edge of the rear wall 22 whether the rear wall is the same height as the other walls or not.

A forwardly and upwardly inclined trans- 25 verse rear supporting plate 35 (Fig. 1) is secured between said side walls with its lower edge flanged as at 36 and engaging under the lower end of said strips 25 and 26. The upper edge 37 of the plate is nearly mid- 30 way between the front and rear walls 21 and 22, slightly nearer the rear wall. Said plate 35 is provided with a pair of openings 39 forming therebetween a locating bar 40 adapted to engage said tabs 9 (Fig. 6), or 35 between the tabs if the leaves are off-set from each other.

The side plate 20 opposite to said upper guide 27 is cut away to form a key receiving opening 42 for permitting the insertion of a 40 key to said key holes 13 for unlocking the posts when the loose-leaf book is resting on said strips 25 and 26 as stated.

A forwardly and downwardly inclined forward supporting plate 45 (Fig. 1), sup- 45 ported between said side walls extends from the upper edge 37 of said rear supporting plate and is formed with a forward flange 46 joining the side walls near the lower edges about the distance of one fourth the 50 length of the side wall from said forward wall 21. Said forward plate is provided with a pair of manipulating openings 49 forming therebetween a positioning bar 50 joining said locating bar 40 and adapted to 55 engage and separate the tabs 9 (Fig. 6). Forward supporting strips 51 (Fig. 1), on the inner face of the side walls, extend from said flange 46 of the forward plate to the upper edge of the front wall 21.

60 The major portion of said side walls 20 between said forward plate 45 and said forward strips 51 is cut away thereby forming large triangular guide-door openings 53 having their lower edges near and parallel to 65 said plate 45 and strips 51. A triangular

guide-door 54 hinged to the forward inclined edge of each of said door openings 53 is provided with an inwardly pressed guide panel 55 slightly spaced from said strip 51 and adapted when the cover board 18 (Fig. 6) is 70 resting on said forward guide strips 51 to engage over the cover board and position the loose-leaves away from the edge of the cover board as the leaves are applied. Said doors 54 open outwardly, for the insertion of the 75 cover board and the removal of the book. Cam latch buttons 57 pivoted on the outer face of each wall are adapted to engage the upper rear corner of the doors to hold them closed. 80

A key hole 58 is provided in each side wall just above the lower ends of the forward strips, for the insertion of the key into the key-hole 13 of the binder for locking the parts before the loose-leaf book is removed 85 from the tray.

The operation of the device is very simple. The bound and locked loose-leaf book or binder is placed in the tray with its rear cover board resting under the guide strip 27 90 and upon the strips 25 and 26 and the extensions 32, the forward face of the leaves or sheets being exposed and their inner edges against the locating bar 40, the key holes 13 of the clamping bars of the binders being 95 exposed by the opening 42.

A key is then inserted through the opening 42 into the key holes, and posts 16 are unlocked, whereupon the posts and the forward cover board 18 are removed. The forward cover boards are then placed upon the supporting strips 53, as in Fig. 6, and the doors 54 are closed and latched. 100

The leaves or sheets are then taken up one by one or in groups and deposited in the forward part of the tray with their tabs on either the one side or the other of the positioning bar 50. 105

All of the sheets on which items are entered are off-set with their tabs on one side 110 of the positioning bar, and those on which items are not so entered placed face down with their tabs on the other side of the bar, later the off-set sheets may be examined for verification or may be otherwise treated as 115 occasion may require.

After all of the sheets have been placed in the forward part of the tray, the rear cover board is placed thereon, the posts replaced and locked, either with or without 120 leaving the leaves off-set from each other, since there are only two posts and they always align with the middle perforation and one of the side perforations.

After the posts are thus locked in place, 125 the doors 54 are opened and the bound loose-leaf book removed, the openings 49 permitting one hand to grasp the inner edge of the book.

Obviously, the operation of off-setting of 130

the loose-leaves, or other features of the invention will be found useful in many operations other than those relating to accounting.

I claim:

5. 1. In combination, downwardly and forwardly inclined rear supporting strips; an upwardly and forwardly inclined transverse rear supporting plate having its rear edge engaging the lower end of said strips, with 10 openings forming therebetween a locating bar transverse to the plate; a downwardly and forwardly inclined forward supporting plate extending from the upper edge of said rear plate and provided with openings forming 15 a positioning bar joining said locating bar; upwardly and forwardly inclined forward supporting strips extending from the lower edge of the forward plate; and guide panels slightly spaced from the forward 20 strips.
2. In combination, front, rear and side walls; a pair of forwardly and downwardly inclined supporting strips secured to the inner face of said side walls and having 25 their upper ends meeting the upper edge of said rear wall and the front end extending to near the bottom edge of the side walls about a fourth of the length of the side wall from the rear wall, the lower end portion of 30 one of said strips being trough-shaped and opening inwardly to form an upper guide above and parallel to the supporting strip and spaced therefrom about the thickness of the cover board of a loose-leaf book; a forwardly and upwardly inclined transverse rear supporting plate secured between said 35 side walls and engaging the lower end of said strips; a downwardly and forwardly inclined forward supporting plate joining said 40 rear plate; and forwardly and upwardly inclined forward supporting means forward of said forward plate.
3. In combination, side members; a pair of forwardly and downwardly inclined supporting strips secured on the inner face of 45 said side members, a portion of one of said strips being trough-shaped and opening inwardly to form an upper guide above and parallel to the supporting strip and spaced 50 therefrom; and a forwardly and upwardly inclined transverse rear supporting member having its rear edge disposed near the lower end of said strips.
4. In combination, side walls; front and 55 rear walls; downwardly and forwardly inclined rear supporting strips secured thereto and a forwardly and upwardly inclined transverse rear supporting plate secured between said side walls with its lower edge 60 flanged and engaging under the lower end of said strips and its upper edge nearly midway between the front and rear walls, slightly nearer the rear wall, said plate being provided with a pair of separated openings thereby forming therebetween a locat- 65
- ing bar adapted to engage tabs of loose-leaves of a loose-leaf book resting on said strips with its inner edge against said plate.
5. In combination, downwardly and forwardly inclined rear supporting means; and a forwardly and upwardly inclined transverse rear supporting plate having its lower edge near the lower part of said means, said plate being provided with a pair of separated openings, thereby forming a locating bar transverse to said plate. 70
6. In combination, rear and side walls; forwardly and downwardly rear supporting strips on the inner face of the side walls, one of said side walls being cut away above the supporting strip to form a key receiving opening; and an upwardly and forwardly inclined rear supporting plate between 80 said side walls and joining said strips.
7. In combination, side walls; forwardly and downwardly rear supporting means on the inner face of the side walls, said side wall above said means being cut away to form a key receiving opening; and a supporting member near the forward part of 90 said means.
8. In combination, side walls; and supporting means mounted between said walls, one of said side walls above said means being cut away to form a key receiving opening. 95
9. In combination, a pair of side walls; a rear end wall having its upper edge lower than the upper edges of the other walls; forwardly and downwardly inclined rear supporting strips secured to said side walls and joining the upper edge of said rear wall; an upwardly and forwardly inclined rear supporting plate between said side walls and joining said strips; a hinged plate 100 hinged to the upper edge of said rear wall in the plane thereof and adapted to fold over against said supporting strips; and a binding wire beaded in the upper and side edges of said hinged plate and having a 110 guide extension extending down against the outer face of the rear wall when the hinged plate is up, and extending approximately in alignment with said supporting strips when the hinged plate rests on the strips. 115
10. In combination, forwardly and downwardly inclined supporting means; an upwardly and forwardly inclined rear supporting member extending from near said means; a hinged member adapted to fold over against said supporting means; and guide extensions secured to said hinged member and extending down when the hinged member is up, and extending approximately 120 in alignment with said supporting means when the hinged member rests on said means. 125
11. In combination, downwardly inclined supporting means; a supporting member near the lower end of said means; a movable member; and guide extensions secured to 130

- said movable member and adapted to extend approximately in alinement with said supporting means.
12. In combination, a tray comprising front and side walls; rear supporting means in the rear of the tray; an upwardly and forwardly inclined rear supporting plate between said side walls and joining said means and provided with a locating bar; a forwardly and downwardly inclined supporting plate supported between said side walls and extending from the upper edge of said rear supporting plate and extending the lower edges of the side walls and provided with a pair of manipulating openings forming therebetween a positioning bar joining said locating bar; and forward supporting means extending from near the lower part of the forward plate to near the upper part 20 of the front wall.
13. In combination, side walls; rear supporting means at the rear of the walls; a rear supporting member between said side walls and forward of said means; a forwardly and downwardly inclined supporting plate supported between said side walls and extending from near the upper part of said rear supporting member and provided with a pair of manipulating openings and a positioning bar transverse to the plate; and forward supporting means near the forward edge of the plate.
14. In combination, side walls; rear supporting means at the rear of the walls; a rear supporting member between said side walls and forward of said means; a forwardly and downwardly inclined supporting plate supported between said side walls and extending from near the upper part of said rear supporting member and provided with a pair of manipulating openings and a positioning bar transverse to the plate; and forward supporting strips extending upwardly from the forward edge of the plate, 40 one of said side walls being provided with a key hole above and near the meeting point of said strips with the plate.
15. In combination, side walls; a forwardly and downwardly inclined supporting plate supported between said side walls; and
- forward supporting means near the forward edge of the plate, one of said side walls being provided with a key hole above the lower edge of said plate, and an opening above said key hole. 55
16. In combination, side walls; a forwardly and downwardly inclined supporting plate supported between said side walls; and forward supporting means near the forward edge of the plate, one of said side walls 60 being provided with a key hole above the lower edge of said plate.
17. In combination, a downwardly and forwardly inclined supporting member; forwardly and upwardly inclined forward supporting means extending from near the lower edge of said member; and a hinged guide member disposed above and slightly spaced from said means and adapted when a cover board of a loose-leaf book is resting on said means to position loose-leaves 70 away from the edge of the cover board.
18. In combination, side walls; supporting member disposed between the side walls; and inclined supporting strips remotely spaced apart to leave a wide open space therebetween and supported on the inner face of the side walls and extending downwardly to near the lower edge of said member; said side walls serving to position loose-leaves on said strips. 80
19. In combination, forwardly and downwardly inclined rear supporting strips remotely spaced apart to leave a wide open space therebetween; a transverse rear supporting member with its lower part near the lower end of said strips; a forwardly and downwardly disposed forward supporting member extending from the upper part of said rear member; forward supporting strips 85 remotely spaced apart to leave a wide open space therebetween and extending forwardly and upwardly from near the lower edge of said forward member and means serving to position loose-leaves on said strips. 90
